PUMP AND ROTARY CONSTRUCTION

Harold B. Schultz, South Bend, Ind., assignor to The Bendix Corporation, South Bend, Ind., a corporation of Delaware

Filed Sept. 21, 1961, Ser. No. 139,712

3 Claims. (Cl. 103—217)

The present invention relates to an inexpensive combination pump and reservoir construction; and more particularly to a combination positive displacement pump and reservoir for producing small flow rates of a high pressure hydraulic fluid in a closed circuit.

An object of the present invention is the provision of a new and improved combination hydraulic pump and reservoir which is simple in its design, rugged in its construction and inexpensive to manufacture.

A further object of the present invention is the provision of a new and improved pump of the above described type wherein the housing for the pump and reservoir is formed by means of a casting having a generally cup-shaped cavity therein opening into one side surface of the housing, and which includes a cup-shaped side cover plate which closes off the pump and reservoir.

A still further object of the present invention is the provision of a new and improved pump of the immediately above described type wherein the housing includes a shaft receiving opening extending generally parallel to the reservoir cavity, and wherein the cover plate overlies the end of the shaft opening to provide lubrication from the reservoir.

A still more particular object of the present invention is the provision of a new and improved pump of the immediately above described type wherein the open end of the housing is machined off to provide a thrust abutment for the pump's shaft, and to provide a sealing abutment arrangement for the cover plate.

Still another object of the present invention is the provision of a new and improved combination pump and reservoir construction of the above described type wherein the side cover plate acts as a retainer for the pump's shaft.

The invention resides in certain constructions and combinations and arrangements of parts; and further objects and advantages will become apparent to those skilled in the art from the following description of the preferred embodiment described with reference to the accompanying drawing forming a part of the specification, and in which:

FIGURE 1 is a side elevational view of a combination hydraulic pump and reservoir with its end cover plate removed and a section broken away to show the internal workings of the pump;

FIGURE 2 is a cross sectional view of the complete pump including the cover plate taken approximately on the line 2—2 of FIGURE 1; and

FIGURE 3 is a diametric view of the pump shaft, pump pin and interconnecting structure.

The combination pump and reservoir shown in the drawing is intended to be used in the closed hydraulic circuit shown in my copending application Serial No. 135,489 filed September 1, 1961 now U.S. Patent No. 3,074,383. As such the pump is intended to provide a discharge pressure from between 1400 to 1800 p.s.i.

The housing of the combination pump and reservoir shown in the drawing is formed by means of a single generally shallow cup-shaped casting 10 which is closed off by means of an end cover plate 12. The lower end of the casting 10 has a shaft opening 14 extending through the casting between its opposite closed and open end sides, and the reservoir cavity 16 is cast above and around the boss portion 18 through which the shaft opening 14

2

extends. The lip on the open end of the cup shaped casting 10 is provided with a cylindrical flange 20, and the open end surface of the casting 10 is finish machined in a flat plane to provide a suitable abutment surface 21 for the end cover plate 12. The radially outer surface of the cylindrical flange 20 is also machined cylindrical while chucked for the preceding machining operation to receive the cylindrical sides 22 of the end cover plate 12. A corner groove 24 is provided at the outside intersection of the cylindrical flange 20 and the finish machine end surface 21 to receive a ring seal 28 which effectively seals off the side surface of the casting 10. The end cover plate 12 may be held in place in any suitable manner, and as shown in the drawing is secured by means of a single machine screw 30 which is suitably threaded into an integrally formed boss 32 which projects out of the closed end 34 of the casting 10 and is machined off flush with the finished machine end surface 21 of the pump. The cover plate 12 bears against the end of the boss 32 and a suitable seal 36 is positioned in a groove 38 in the end of the boss 32 to suitably seal off the opening through the cover plate 12.

As previously mentioned, the pump is intended to be used in a closed hydraulic circuit and in order that the circulating fluid may be continuously filtered, a short annular partition 40 extends about the integral boss 32 and is finish machined off as at 42 to sealingly abut the bottom annular end of a donut shaped filter 44. Filter 44 is held down upon the annular end surface 42 by means of a cup-shaped washer 46—the outer flange of which engages the top surface of the filter 44, and the inner end of which has an opening through which the boss 32 extends. A suitable annular seal 48 is positioned in the bottom of the cup-shaped washer 46, and the cup-shaped washer is held down into sealing engagement with the top surface of the filter 44 by means of a coil spring 50 interpositioned between the cover plate 12 and the seal 48. The return fluid is conducted to the central opening 52 of the filter through a return connection 54 which is pressed into an opening 56 communicating with the inside surface of the short partition 40 through a fillet of metal 58 cast integrally with the bottom end wall 34 of the housing 10. Return fluid therefore flows into the moon shaped opening 60 formed inwardly of the short partition 40 to flow up into the central opening 52 of the filter, from whence it flows outwardly through the filter material to reach the reservoir cavity surrounding the filter. By means of this arrangement all hydraulic fluid reaching the portion of the cavity in which the moving pump parts are located is suitably filtered; and a removable filler cap 62 is provided in the top surface of the pump casting 10 to permit a suitable level to be maintained.

The pumping mechanism shown in the drawing is of a positive displacement reciprocating type that is driven off of a shaft 64 suitably journaled in the shaft opening 14 by means of sleeve bearings 66 and 68 that are positioned on opposite sides of a centrally located eccentric portion 70 of the shaft. The drive portion of the shaft extends outwardly of the closed end of the casting 10 to receive a suitable driving pulley not shown and which is connected thereto in a well known manner. The shaft opening 14 in the boss 18 which surrounds the eccentric portion 70 of the shaft is suitably enlarged or machined out to receive the reciprocating structure of the pump as will later be explained. The enlarged section 72 is communicated with the reservoir cavity 16 by means of a cylindrical opening 74 through which the reciprocating structure extends. Oil from the reservoir cavity 16 is therefore always in communication with the reciprocating structure and the center portion of the shaft 64. Shaft

opening 14 adjacent the outer end of the shaft 64 is suitably enlarged or counterbored as at 76 to receive an oil slipper seal 78, and a short drilled passage 80 communicates the reservoir chamber 16 at the base of the counterbore 76 and thereby lubricates the outer end of the shaft 64.

A suitable thrust bearing may be provided for the shaft 64 in any number of ways, and is most conveniently provided by causing the inner end of the shaft 64 to project out of the machined end surface 26 of the pump to receive a thrust washer 82 which is integrally connected to the shaft 64 and bears against the finished machine surface 26. As shown in the drawing, the inner end of the shaft 64 is provided with an annular extension 84 which extends out through the central opening of the washer 82 and is peened over to affix the washer to the shaft. Inward movement of the shaft 64 is conveniently restrained by means of a ball bearing 86 that is positioned in a drilled socket 88 in the inner end of the shaft 64 in such manner that the ball 86 projects out of the shaft to be engaged by the cover plate 12. The cover plate 12 may be made in any suitable manner, and as shown in the drawing is formed by means of a sheet metal stamping which has sufficient flexibility to yieldingly provide a hold-down force of a desired intensity. Cover plate 12 is dished outwardly in the region surrounding the machine screw 30 and overlying the end of the shaft 64, so that the ball bearing 86 and thrust washer 82 is bathed in the filtered oil of the reservoir cavity 16.

The reciprocating pump structure is generally housed within a cylindrical boss 90 formed as an integral part in the bottom of the casting 10 opposite the central opening 74 leading to the eccentric portion 70 of the shaft 64. The cylindrical boss 90 is provided with a central opening 92 therethrough which is in line with the opening 74 in the boss 18, and which is counterbored as at 94 to receive a stack-up of machined elements which together form the pumping structure of the unit. The fluid pressurizing cylinder chamber of the pump structure is formed by means of a flanged body 96 having an inwardly projecting portion 98 that is provided with an accurately dimensioned axially extending opening 100 therethrough. The flange portion 102 of the body 96 is seated up against the shoulder 104 provided by the counterbore 94, and the central opening 100 slidably receives an accurately ground cylindrical piston member 106 which is adapted to reciprocate in the opening 100. The outer end of the opening 100 is suitably counterbored as 103 to receive an inlet check valve 110 and the outer end of the flange portion 102 is provided with a reduced diameter section 112 to receive the cup-shaped end of a porting and hold-down member 114. The sidewalls of the inner cup-shaped portion of the porting and hold-down member 114 is slipped over the reduced diameter section 112 of the cylinder body 96 with a suitable seal 116 positioned therebetween to seal off the outer end of the counterbore 103. The inner end of the cup-shaped portion abuts the shoulder 118 formed by the reduced diameter section 112 to bias the flange 96 into engagement with the inner shoulder 104. A suitable coil spring 120 is positioned between the bottom of the counterbore 103 and the check valve 110 to bias the check valve 110 into sealing engagement with the bottom surface of the cup-shaped portion of the porting hold-down member 114. Suitable drilled passageways 122 and 124 are provided through the sides of the boss 90 and porting member 114 to communicate with an axially extending passageway 126 which extends through the hold-down member to communicate fluid from the reservoir 16 to the surface of the inlet check valve 110. The bottom surface of the cup-shaped portion which is engaged by the inlet check valve 110 forms an inlet valve seat for closing off the inlet passages 122 and 126 from the counterbore 103 during the discharge stroke of the piston member 106.

An unloading pin 128 is slidably received in the outer end of the axial passageway 126, for reasons which will later be explained; and the inner portion of the opening 126 between the passageway 124 and the inlet check valve 110 is slightly enlarged to provide a free passage of fluid around the outside of pin 128. The outer end of the porting and hold-down member 114 is provided with a machined annular flat face 130, and an axially outwardly extending boss 132 through which the opening 126 extends. The periphery of the suction poppet 110 is serrated to permit passage of fluid around its outside edges, and a diagonal discharge passage 134 is provided in the porting member to communicate discharge from the counterbore 103 to the center of the annular machined surface 130 adjacent one side of the axial boss 132. A discharge poppet 136 having a molded rubber seal 138 on its outer periphery is positioned for sealing engagement with the machine surface 130 in the region surrounding the diagonal opening 134 to prevent the return of fluid through the diagonal discharge passage 134. The discharge poppet 136 is biased into sealing engagement with the machine surface 130 by means of a coil spring 140—which in turn is held in position by means of an annular plastic hold-down member 142 that is positioned around the boss 132. The plastic hold-down member 142 has a cylindrical opening 144 for receiving and guiding the poppet 136, and further includes a small discharge passage 146 in its outer face to permit passage of fluid to the outer end of the opening 94 in the boss 90.

The outer end of the opening 94 is closed off by a threaded cup-shaped cap 148 which effects a suitable seal with respect to the sidewalls of the bore 94 and sandwiches the hold-down members 142, porting member 114 and flange 102 of the cylinder body 96 between the inner shoulder 104 of the housing and the threaded end cap 148. The internal cavity of the cup-shaped end cap 148 receives the outer end of the unloading pin 128, which is biased outwardly by means of a coil spring 150 that is positioned between a suitable inner spring retainer 152 that abuts the end of the boss 132, and an outer spring retainer 154 suitably affixed to the outer end of the unloading pin 128. A suitable seal is provided between the pin 128 and the outer end of the boss 132. The spring 150 normally holds the outer spring retainer 154 into abutment with the bottom of the cup-shaped opening in the threaded cap 148 until sufficient discharge pressure is received from the discharge opening 146 to produce a differential pressure across the opposite ends of the unloading pin 128 to overcome the force of the spring and move the pin inwardly to unseat the suction poppet 110 from its seating surface. Unloading pin 128 and coil spring 150 thereby provide a simple arrangement for unseating the suction poppet 110 at a predetermined discharge pressure and thereby unload the pump. The threaded cap 148 further includes a conventional outlet connection 156 by means of which it can be suitably connected to the hydraulic distribution system.

The piston pin 106 is caused to be reciprocated by means of the eccentric portion 70 of the shaft 64 through a connecting arm arrangement which is extremely simple and which automatically locks and holds the parts together. This connecting arm structure comprises an abutment link 160 which has an inner end shaped to conform to the eccentric shaft portion 70, and which extends through the opening 74 to receive the inner end of the piston pin member 106. The abutment link 160 has a cylindrical opening 162 spaced slightly inwardly from its outer end and extending transversely through the abutment link 160. The outer end of the abutment link 160 is provided with a vertical milled slot 164 which intersects and opens into the cylindrical opening 162. The inner end of the piston member 106 extends through slot 164 and is received in a short bore 166 of approximately the same size as the pin 106 and which extends only part ways through a cylindrical wrist pin 168 that is positioned

in the opening 162. The side surfaces of the slot 164 prevent lateral movement of the abutment link 160 relative to the piston 106, and the piston 106 in turn holds the wrist pin 168 within the abutment link 160. Withdrawal of the inner end of the pin 106 out of the connecting arm structure is prevented by means of a piston return spring 170 positioned between the bottom of the cylinder body 96 and a spring retainer 172 which is suitably affixed to the piston pin 106. Piston return spring 170 is strong enough, and serves the additional function, to at all times biasing the inner end of the connecting or abutment link 160 against the eccentric surface 70 of the shaft 64 so that no additional holdown structure need be provided. It will be noted that the pump's reciprocating structure is assured of complete and proper lubrication, inasmuch as the reciprocating structure is positioned within the portion of the reservoir chamber 16 which at all times has filtered hydraulic oil contained therein. The reciprocating parts above described are completely open to view when the end cover plate 12 of the structure is removed, and further are readily accessible during assembly.

As previously mentioned, the pump and reservoir construction shown in the drawing is intended to be used in a closed hydraulic circuit wherein return flow enters the inlet connection 54 to flow through the moon shaped opening 60 in the bottom of the reservoir cavity, through the central opening of the filter 44, and out into the reservoir chamber 16. As previously mentioned, the center section of the shaft 64, as well as the portions on the outside of its bearings 66 and 68, are open to the reservoir chamber 16 so that complete lubrication is always assured. The shaft 64 may be rotated in any suitable manner, as for example by means of a V-belt pulley so that its eccentrically located center portion 70 forces the connecting link 160 towards the pump structure in the boss 90 to cause the piston pin 106 to displace fluid from its receiving bore 100. The outward stroke of the pin 106 displaces fluid from the counterbore 108 out through the discharge passage 134, to lift poppet member 136 out of engagement with its seating surface 130 and thereby flow to the discharge connection 156.

After the eccentric 70 reaches top dead center, the spring 170 biases the piston pin 106, wrist pin 168, and connecting link 160 inwardly with sufficient force to hold the connecting link 160 against the eccentric portion 70 of the shaft 64. This causes the piston pin 106 to be retracted in its receiving bore 100 and thereby draw fluid from the reservoir chamber 16 through the passages 122, 124, and 126 past the intake valve 110 and into the counterbore 108. The next 180° cycle of the shaft 64 thereafter produces a discharge stroke to repeat the cycle.

When the pressure in the outlet connection 156 reaches a predetermined value, say 1400 p.s.i. sufficient differential pressure across the unloading pin 128 exists to overcome the force of the coil spring 150 and force the pin 128 inwardly by an amount which lifts the inlet check valve 110 out of engagement with its seating surface and thereby unload the pump. As long as this predetermined pressure exists in the outlet connection 156, the inlet check valve 110 remains out of engagement with its seating surface so that the reciprocation of the piston pin 106 alternately sucks and discharges fluid to the reservoir 16 without building up pressure and without absorbing any appreciable amount of energy from the shaft 64.

It will be apparent that the objects heretofore enumerated as well as others have been accomplished; and that there has been provided a pumping structure, as well as a combination pump and reservoir construction which is extremely simple in design, rugged in construction and inexpensive to manufacture.

While the invention has been described in considerable detail, I do not wish to be limited to the particular construction shown and described; and it is my intention to cover hereby all novel adaptations, modifications and ar-

rangements thereof which come within the practice of those skilled in the art to which the invention relates.

I claim:

1. A pump construction comprising: a generally horizontal cylindrically shaped housing having an internal cup-shaped reservoir cavity opening into one end surface of said housing, the open end and closed end of said housing forming the opposite sides of said pump construction, said housing including an integral boss portion extending between said ends adjacent the lower side of said housing, a shaft receiving opening in said boss portion extending between said ends of said housing, a shaft journaled in said opening and projecting from said closed end of said housing, said housing having a generally cylindrically shaped sidewall surrounding said reservoir cavity and said shaft, an annular recess machined in the outside surface of said cylindrical sidewall adjacent said open end, a cup-shaped cover plate with its bottom covering said open end and its sidewall extending over said recess in said cylindrical wall, said cover plate being dished outwardly to form a lubricant passage a seal positioned between said sidewall of said cover plate and said recess, pump means driven by said shaft and opening into said cavity to be immersed in its fluid and receive suction therefrom, and a ball thrust bearing positioned between said shaft and said cover plate such that said ball thrust bearing is in to said lubricant passage.
2. A pump construction comprising: a generally horizontal cylindrically shaped housing having an internal cup-shaped reservoir cavity opening into one end surface of said housing, the open end and closed end of said housing forming the opposite sides of said pump construction, said housing including a first integral boss portion extending between said ends adjacent the lower side of said housing, a shaft receiving opening in said boss portion extending between said ends of said housing, a shaft journaled in said opening and projecting from said closed end of said housing, said housing having a generally cylindrically shaped sidewall surrounding said reservoir cavity and said shaft, said shaft having a flange bearing against said boss portion of said housing, an annular recess machined in the outside surface of said cylindrical sidewall, a cup-shaped cover plate with its bottom covering said open end and its sidewall extending over said recess, said cover plate being dished outwardly to form a radial lubricant passage terminating outwardly adjacent said sidewall of said housing where it underlies said bottom of said cover plate, a seal positioned between said sidewall of said cover and said recess, pump means driven by said shaft and opening into said cavity to be immersed in its fluid and receive suction therefrom, and a ball thrust bearing positioned between said shaft and said cover plate in said lubricant passage.
3. A pump construction comprising: a generally horizontal cylindrically shaped housing having an internal cup-shaped reservoir cavity opening into one end surface of said housing, the open end and closed end of said housing forming the opposite sides of said pump construction, said housing including a first integral boss portion extending between said ends adjacent the lower side of said housing, a shaft journaled in said opening and portion extending between said open and closed ends of said housing, a shaft journaled in said opening and projecting from the closed end of said housing, said housing having a generally cylindrically shaped sidewall surrounding said reservoir cavity and said shaft, said housing having a second integral boss portion extending between said open and closed ends and located generally centrally of said sidewall, said open end of said housing being finish machined across the end of said sidewall and said first and second integral boss portions, said shaft having a thrust washer bearing against said machined open end and said first boss portion, an annular recess machined in the juncture of said outside surface of said cylindrical sidewall and said machined end surface, a

cup-shaped cover plate with its bottom covering said open end and its sidewall extending over said recess, a seal positioned between said sidewall of said cover and said recess, said cover plate being formed with a passage extending between said second boss portion and said housing sidewall to overlie said first boss portion pump means driven by said shaft and opening into said cavity to be immersed in its fluid and receive suction therefrom, a ball thrust bearing positioned between said shaft and said cover plate in said passage, an annular filter surrounding 10 said second integral boss portion and sealed with respect to said bottom closed end of said cavity, means sealing the top of said annular filter to said second integral portion, a return connection communicating with the central opening of said annular filter and a means communicating 15 said passage with said filter to provide a contaminant free

lubricant for said ball thrust bearing and said thrust washer.
